GEOCHEMICAL EXPLORATION

Leo Horvitz, Houston, Tex., assignor to Esme E.
Rosaire, Houston, Tex.No Drawing. Application June 24, 1937.
Serial No. 150,103

2 Claims. (Cl. 23—230)

This invention relates to prospecting by a study of the emanations, or modified emanations which are found in the earth adjacent to buried deposits of oil and gas. In particular, this invention relates to an exploration method which is based upon the amount of water resulting from the combustion of gases drawn or forced from the soil in geochemical prospecting.

An object of the invention is to provide a method of chemical analysis of gas samples for the purpose of detection of minute hydrocarbon contents.

Another object is, in the method of geochemical exploration and research, to improve the laboratory processes so that the sensitivity to the presence of hydrocarbons is increased several times over previously practiced art, a valuable contribution when seeking small concentrations of such substances.

A more specific object is to analyze gases for hydrocarbon and hydrogen content by the method of combustion and measure the amount of products of combustion, particularly water.

Still another object is to provide a rapid and economical laboratory technique, suitable for use in the art of geochemical prospecting wherein a single indication serves satisfactorily to reveal the presence or absence of the components sought.

There are references, particularly in the Russian literature, pertaining to soil gas prospecting. A reconnaissance method of prospecting has also been proposed in which gas is drawn from the soil, the carbon dioxide normally present there removed, the gases subjected to the influence of a

been found that hydrogen is frequently encountered and is of significance, and since hydrogen burns without forming carbon dioxide, the method described above will not show the presence of hydrogen.

In the present invention the disadvantages of previously known methods are obviated by analyzing the products of combustion for water vapor formed during combustion of a previously dehydrated sample. The first step of the process of the invention is therefore the removal of all water vapor from the gaseous sample that is to be subjected to analysis. This step may be carried out by any of several well known methods. The water free sample is then burned, as by contact with a hot platinum wire, or filament, the products of combustion being thereafter analyzed quantitatively for water vapor formed during combustion. This quantitative determination of water vapor formed may likewise be made by any of several methods known in the art.

The advantages of the invention become evident from a study of the chemistry involved. In the following table, the first column gives the equations involved in the combustion of hydrogen, methane, ethane and propane. Other constituents could be included but these given are sufficient to illustrate the invention.

In the second column is given the ratio of volume of water vapor to the volume of the particular constituent of the gaseous mixture. In the last column is the ratio of volume of carbon dioxide vapor to the volume of the substance burned.

Ratio of volumes

1	$2H_2 + O_2 \rightarrow 2H_2O$	$H_2O/H_2 = 1$	$CO_2/H_2 = 0$
2	$CH_4 + 2O_2 \rightarrow 2H_2O + CO_2$	$H_2O/CH_4 = 2$	$CO_2/CH_4 = 1$
3	$2C_2H_6 + 7O_2 \rightarrow 6H_2O + 4CO_2$	$H_2O/C_2H_6 = 3$	$CO_2/C_2H_6 = 2$
4	$2C_3H_8 + 10O_2 \rightarrow 8H_2O + 6CO_2$	$H_2O/C_3H_8 = 4$	$CO_2/C_3H_8 = 3$

glowing wire, and then tested either qualitatively or quantitatively for the presence of carbon dioxide, which, if then present, is assumed to have resulted from the combustion of hydrocarbons present.

This method, while useful, has certain disadvantages. For instance, if methane is present, only one volume of carbon dioxide is produced for each volume of methane present; and for the higher hydrocarbons, which are present in much smaller quantities, two volumes of carbon dioxide for each volume of ethane originally present, three volumes of carbon dioxide for each volume of propane present, etc. Further, it has

From a comparison of volume ratios it is evident that the water vapor method is infinitely more sensitive than the carbon dioxide method for detecting hydrogen, since hydrogen does not form any carbon dioxide on combustion. For methane, the sensitivity is twice as great in this method than in the older art, for ethane 50% more sensitive, etc.

While the research leading to this invention, and the invention itself, is directed to a prospecting method, it is evident that the generic object of the invention might well be realized in practice of the invention in other environments such as seeking of leaks around tank farms and pipe lines.

and the special or routine testing for personnel and/or fire hazards in refineries and industrial plants. In fact, combustible dust, such as carbohydrates (cotton, starch and the like), suspended in air can be evaluated quantitatively by the method disclosed herein.

There are cases where knowledge of exact chemical composition is neither necessary nor desirable but where a measure of combustible 10 contents of a gas is needed. Thus a complete, or ultimate, chemical analysis would be superfluous, but the proximate analysis herein described will give all the information needed. It is therefore intended that the description of the preferred embodiment is illustrative only, the invention being limited only by the appended claims and 15 the prior art.

What is claimed is:

1. The method of prospecting for buried hydrocarbon deposits by soil gas analysis which 20 comprises the steps of collecting samples of soil

from the earth near the surface, subjecting the samples to treatment to evolve the significant gases therein, removing from the gases all traces of water, subjecting the dehydrated gas to combustion, and analyzing the products of combustion for water formed by combustion by the entire free and combined hydrogen in the dry gas as an indication of relative proximity of the soil samples to the sought deposits. 5

2. The method of prospecting for buried hydrocarbon deposits by gas analysis which comprises the steps of collecting samples of soil from the earth, subjecting the samples to treatment to evolve the significant gases therein, removing from the gas all traces of water, subjecting the dehydrated gas to combustion, and analyzing the products of combustion for water formed by combustion of the fire and combined hydrogen in 10 the dry gas. 15

LEO HORVITZ. 20

CERTIFICATE OF CORRECTION.

Patent No. 2,198,619.

April 30, 1940.

LEO HORVITZ.

It is hereby certified that error appears in the printed specification of the above numbered patent requiring correction as follows: Page 2, second column, line 18, claim 2, for the word "fire" read --free--; and that the said Letters Patent should be read with this correction therein that the same may conform to the record of the case in the Patent Office.

Signed and sealed this 9th day of July, A. D. 1940.

(Seal)

Henry Van Arsdale,
Acting Commissioner of Patents.
